UNITED STATES PATENT OFFICE.

JOHN W. MILLET, OF DOLGEVILLE, NEW YORK, ASSIGNOR TO ALFRED DOLGE, OF SAME PLACE.

FULLING-MACHINE.

SPECIFICATION forming part of Letters Patent No. 448,536, dated March 17, 1891.

Application filed August 7, 1890. Serial No. 361,277. (No model.)

To all whom it may concern:

Be it known that I, JOHN W. MILLET, a citizen of the United States, residing at Dolgeville, in the county of Herkimer and State of New York, have invented new and useful Improvement in Fulling-Machines, of which the following is a specification.

This invention relates to improvements in fulling-machines; and the invention consists in the details of construction set forth in the following specification and claims, and illustrated in the accompanying drawings, in which—

Figure 1 is a face elevation, partly in section along *x x*, Fig. 2, of a fulling-machine containing my invention. Fig. 2 is a section along *y y*, Fig. 1. Fig. 3 is a section along *v v*, Fig. 1. Fig. 4 is a section along *w w*, Fig. 3. Fig. 5 is a detail sectional view of a lag. Fig. 6 is a plan view of a lag. Fig. 7 is a face view of a lag.

In the drawings, the letter A indicates a roller whose axle B has a toothed wheel C, engaged by a rack D. A link E connects the rack to a crank-pin F, and as the crank-pin is rotated by the pulley G the rack D is reciprocated so as to roll or oscillate the roller A. This roller rests partly in a trough or vessel H containing soap and water. The contents of the trough or vessel are kept heated by suitable means, such as a steam-coil H⁸.

The felt I has one end sewed or fastened to a rod K. This rod is secured to the roller A by latches L. The latches are U-shaped pieces of metal rotatably secured to the roller A. By placing the rod K into the latches and turning the open portion of the latches toward the center of roller A, Fig. 3, the rod will be secured to the roller. By turning the open portions of the latches outward the rod can be removed from the roller.

The felt I, as seen in Fig. 2, is placed partly about the roller A and is then doubled over upon itself. The free end of the felt rests in the channel or guide M M, formed of two boards suitably connected with and supported by the trough or vessel H. The free end of the felt can readily play back and forth in this guide. As the felt is rolled back and forth by the roller A, it is exposed to the ac-

tion of the lags N. Springs O, coiled about rods P, press the lags against the felt. These rods P are secured to brackets Q, fastened to the trough H, and constitute supporting-guides for the metal-tipped lags. Rims or stops R prevent the lags from being pressed too closely toward the roller A. The lags are independent of one another, so that each lag will respond to any unevenness in the felt. The lags have their ends tipped with brass or metal S to prevent breakage or wear.

While the rod K, with the attached felt, is being secured to a roller A, the body of the felt can be allowed to rest on a suitable board T.

What I claim as new, and desire to secure by Letters Patent, is—

1. In a fulling-machine, the combination of a roller for rolling the felt, a rod and latches for securing the felt to the roller, and mechanism for actuating the roller, substantially as described.

2. In a fulling-machine, the combination, with a roller for rolling the felt, of actuating mechanism, substantially as described, for the roller, and spring-pressed lags arranged independently of one another about said roller, substantially as described.

3. In a fulling-machine, the combination, with a roller for rolling the felt and actuating mechanism for the roller, of lags having their ends tipped with metal and arranged round the roller, supporting-guides for the lags, and springs for pressing the lags toward the roller, substantially as described.

4. In a fulling-machine, the combination, with a roller for holding the felt, of actuating mechanism, substantially as described, for the roller, lags arranged about the roller, and a stop or rim R for keeping the lags a suitable distance from the roller, substantially as described.

5. In a fulling-machine, the combination, with a trough or vessel having a felt channel or guide, of a roller arranged below the channel or guide for holding the felt, actuating mechanism for the roller, and lags arranged about the roller, substantially as described.

6. In a fulling-machine, the combination, with a trough or vessel having a felt channel

or guide, of a roller for rolling the felt, actuating mechanism for the roller, spring-pressed lags arranged about the roller, a stop R for the lags, and a rod K and latches L for securing one end of the felt to the roller, substantially as described.

In testimony whereof I have hereunto set

my hand in the presence of two subscribing witnesses.

JOHN W. MILLET.
